GATE

Glenn A. Duis and Kenneth W. Hermann,
Streator, Ill., assignors to Anthony Company,
Streator, Ill., a corporation of Illinois

Application July 22, 1946, Serial No. 685,391

3 Claims. (Cl. 296—51)

1

This invention relates to a gate for a vehicle body or a bin body.

It has for one object to provide a gate with its construction so arranged that the gate may be pivoted or swung from its top or from its bottom at will.

Another object is to provide a gate with its means so arranged that the gate when swung from the bottom will in one position form a continuous extension of the floor of the bin or vehicle body.

A still further object is to provide a gate supporting means so arranged that the gate when in the extreme open position is practically beneath the body.

Another object is to provide a pivotal support for a lower part of a gate so arranged that when free to do so the pivot of the gate shifts.

Other objects will appear from time to time throughout the course of the specification and claims.

The invention is illustrated more or less diagrammatically in the accompanying drawings, wherein:

Figure 1 is a side elevation showing a body or bin with the gate in closed position, and showing in dot-and-dash line the gate in horizontal position and showing the gate in dotted line in the full open position;

Figure 2 is an end elevation showing the gate supporting means at one side;

Figure 3 is a plan view of the gate supporting means on one side of the body or bin; and

Figure 4 is a section taken at line 4—4 of Figure 1.

Like parts are designated by like characteristics throughout the specification and drawings.

In the particular form here shown, the gate is applied to a body of a truck or vehicle, it might equally be, however, applied to a bin or fixed container. Only so much of the body will be described as is necessary to explain the use and construction of the gate.

The body may be conveniently mounted on a frame which includes longitudinal members 1 and one or more transverse members 2. The body includes side sheet-like members 3 and a bottom sheet-like member 4. The body is secured to the frame in any manner such as welding, riveting, bolting or otherwise.

At their upper edges the sheets which form the sides of the body may be bent over to form thickened stiffening members 5, and at their rear the sheets may be bent about to form a thickened

stiffening frame-like member 6 which is positioned adjacent to the opening.

On each side of the body is positioned a supporting member 7 which is provided with a pair of rearwardly directed arms or branches 8. These branches may be curved as shown in Figure 2, and they are perforated to receive a locking pin 9 which may be fastened to the member 7 by a pin or other flexible member 10. Adjacent the bottom of the body on each side is fixed a pair of pivot members 11. These members are preferably perforated to receive a pin 12.

The gate may be formed of a sheet-like member 13, which is laterally bent as at 14 and downwardly bent as at 15 to engage the re-enforcing end members 16. A stiffening or re-enforcing member 17 may form part of the gate. The exact details of the gate are not an essential part of the invention which may be applied to almost any sort of gate.

At or near the upper edge of the gate on each side is mounted a member 18 provided with a pair of upwardly extending branches 19 between which a pin 20 may be fastened. The pin 20 may, as shown in Figures 1 and 2 particularly, fit between the members 8.

The pin 9, when in the position shown in Figures 1 and 2, will hold the pin 20 in place between the members 8 to complete the hinge.

A chain 21 may be fastened at any suitable point on the body and may be fastened also to the gate to hold it in the horizontal position shown in the dot-and-dash line of Figure 1.

At or near its lower end the gate is provided on each side with a member 22 which, particularly as shown in Figure 2, is outwardly flared. A stiffening or reinforcing portion 23 may be added to or formed integrally with the member 22. A pin 24 projects inwardly from the member 22 and may fit between the members 11.

The locking pin 12, which is adapted to occupy the position shown in Figures 1 and 2, may be fastened by a chain 25 to the reinforcing member 23 or to the member 22. The pin 12 is adapted to be removably seated in suitable perforations in the members 11.

If desired, the gate may be provided along its edges with channel members 26. These channel members, particularly as shown in Figure 4, overlap or embrace the ends of the body side plates 3 or the enlargements 6 on them and thus serve as positioning and leak preventing means to prevent leaking or discharge of the contents of the body.

Although we have shown an operative form of

our invention, it will be recognized that many changes in the form, shape and arrangement of parts can be made without departing from the spirit of the invention, and our showing is therefore to be taken as, in a sense, diagrammatic.

The use and operation of this invention are as follows:

The gate when it is to act merely as a tailgate, for example, for a tipping body will be swung from above and the pin 9 will be in position to hold the pins 19 between the respective members 8 and thus to complete the hinge at the upper end of the body.

When the gate is to be held closed, the pins 12 will be in position between the members 11 and will hold the gate fastened by cooperation with the pins 23. If the gate is now to be swung open from above, the pins 12 are withdrawn and the gate may be swung open, the pins 23 moving out of the space defined between the members 11. If the gate is to be swung from below—that is to say, if it is to be hinged from the bottom—the pins 9 are withdrawn from the members 8 and the gate may then hinge about the pins 23.

The chain 20 will be of such length as to hold the gate in the horizontal or dot-and-dash position of Figure 1. As the gate swings from the closed or upper position toward the horizontal position, the pins 23 slide downwardly along the upper surface of the lowermost member 11 until they fit into the inner end of the space defined between the members 11. This movement brings the bottom of the gate flush against the end of the body frame 1 and the surface of the gate which is then uppermost is substantially on a level with the bottom of the body. Thus if it is desired to shovel or otherwise move material along the bottom of the body, it can be moved continuously and without interruption from the bottom of the body and across and over the surface of the gate, without any spilling between the gate and the bottom of the body.

If the gate is to be lowered to the full lowermost position, the chain 20 is disengaged and the gate is permitted to swing to the dotted line position of Figure 1. In that position the pins 23 still remain in the inner end of the space defined between the members 11 and the gate thus swings so that the major portion of the gate is under the body and is forward of a line drawn vertically along the rearmost portion of the body, and thus if the contents of the body is to be shovelled or otherwise discharged through the open end the gate is out of the way and does not interfere with the discharge and the free fall of material from the body.

The arrangement of the pins 23 and the members 11 is such as to provide two points of retention of the pins 23. When the gate is in the vertical closed position, the members 11 act merely as retainers for the members 23 and as supports for the locking pins 12. When the gate is released at the top and swung downwardly the pins 23 slide inwardly and downwardly between the members 11 until they reach the inner end of the space defined by those members and there the pins 23 find a pivot point which is substantially forward of the point which they occupy when the gate is held closed or is hinged from the upper edge. This construction therefore permits the use of a gate which may hinge from the top or from the bottom and which when hinged from the bottom shifts automatically so that in the

horizontal position it is flush against the body and forms in effect a continuation of the bottom body surface. When in the full lowered position it is largely under the body and out of the way of material falling from the body.

We claim:

1. In combination, members defining a body having an open end, and a gate movably supported therein, hinge members positioned one on said body and one on said gate adjacent the upper end of the gate and including diverging arms on said body, said hinge members comprising rounded parts, and diverging arms adapted to receive said rounded parts, and latch members adapted removably to hold said rounded parts in place, and additional hinge members positioned adjacent the bottom of said gate and including rounded members on said gate, and inclined arm members on said body adjacent the bottom of said body, said last-mentioned arm members adapted as the gate moves to serve as bearings for said last-mentioned rounded members.

2. In combination, members defining a body having an open end, and a gate movably supported therein, hinge members positioned one on said body and one on said gate adjacent the upper end of the gate, said hinge members comprising rounded parts, and diverging arms adapted to receive said rounded parts, and latch members adapted removably to hold said rounded parts in place, and additional hinge members positioned adjacent the bottom of said gate and including rounded members on said gate, and inclined arm members on said body adjacent the bottom of said body, said last-mentioned arm members adapted as the gate moves to serve as bearings for said last-mentioned rounded members.

3. In combination, members defining a body having a floor and an open end, a gate supporting structure at said open end, and a gate movably supported therein, hinge members positioned one on said body and one on said gate adjacent the upper end of the gate supporting structure, and pins on said gate adapted to be removably engaged in said bottom hinge members, and latching means comprising pins engaging said hinge members and when in position to retain said first-mentioned pins in place, said uppermost hinge members comprising diverging parts and said lower hinge members comprising straight parallel parts.
